UNITED STATES PATENT OFFICE.

JOHAN VIKTOR BLOMQUIST, OF STOCKHOLM, SWEDEN.

ART OF PRODUCING STEAM OF HIGH PRESSURE.

1,307,612.

Specification of Letters Patent. Patented June 24, 1919.

Application filed December 28, 1914. Serial No. 879,397.

To all whom it may concern:

Be it known that I, JOHAN VIKTOR BLOMQUIST, a subject of the King of Sweden, and a resident of Stockholm, Sweden, have invented certain new and useful Improvements in the Art of Producing Steam of High Pressure for Power and Heating Purposes, of which the following is a specification.

- 10 To procure a positive reliability of service it is necessary not to expose the direct heating surface of a boiler to so high a temperature that the material is damaged. The higher the pressure of the steam, the more 15 attention must be paid to this circumstance. The greater the strain on the grate, *i. e.*, the more coal that is burnt on the grate, the higher the temperature in the firebox. The 20 temperature of the flue gases may be calculated from the following equation:

$$t = t_0 + \frac{B \cdot W \cdot \eta}{Q \cdot cp}$$

25 in which B indicates the weight in kilograms of fuel holding W calories per kg. and square meter of the grate surface η = the efficiency of the combustion; Q =the weight of the flue gases generated by the combustion; cp =their specific heat, t_0 =the 30 temperature of the admitted air, and t =the temperature of the flue gases.

35 The equation is true, irrespective of eventually ensuing dissociation, if the firebox is surrounded by walls entirely impervious to heat. If a body permeable to heat is introduced in the firebox, it will radiate "negative" heat that reduces the temperature, and then the temperature of the firebox may be 40 calculated from the following equation:

$$Q \cdot cp \cdot t = B \cdot W \cdot \eta - f \cdot s \cdot \left[\left(\frac{a+t}{100} \right)^4 - \left(\frac{a+t_1}{100} \right)^4 \right],$$

45 wherein t_1 indicates the outer temperature of the body introduced, and s =the constant of radiation which in steam boilers=4, and f =the size of the radiating surface in square meters.

50 From this it is evident that the larger the reflecting surface, the lower the temperature of the flue gases or the firebox will be. Thus, by rightly proportioning the direct heat surface in a boiler, the temperature of the firebox may be determined at will in advance.

55 In a water tubular boiler, the reflecting surface is not much larger than the grate

surface, when the projection of the direct heating surface is of the same size as the latter one. A cylindrical boiler is more advantageous in this respect, and the reflecting surface may be still more enlarged by putting the same in rotation.

If the axis of the boiler is horizontal and the projection of the boiler on a horizontal plane is of the same size as the grate surface, 60 the reflecting surface will be π times larger than the grate surface, and this will bring the advantage that the grate surface might be strained to an essential degree without the boiler plate being injured. The reflecting 65 surface may be still more increased by placing several such rotating cylinders in the same firebox, and by this arrangement it will be possible in advance, at will, to determine the temperature of the firebox at a certain quantity of heat developed on the grate. It is 70 evident that the grate surface at a certain outside temperature of the rotating cylinders 75 may be exposed to a greater strain the more cylinders are placed in the firebox.

75 However, the mean temperature of the cylinders is also dependent on the velocity of the transference of heat from the boiler shell to the water. If the water is in a boiling condition the co-efficient of transference 80 of heat from the plate to the water amounts to about 10,000 calories per square meter, degree of difference of temperature and per hour, while on the other hand, when the water is not boiling, the transference of heat 85 is considerably inferior, that is to say, the plate must be hotter to transfer a certain quantity of heat in the latter case than in the former. Therefore the water ought to be brought into a boiler if possible in a boiling 90 state, so that the boiler plate may be protected against too high a temperature.

95 The drawings represent a convenient apparatus for carrying out this process of generating steam, wherein Figure 1 is a longitudinal section of the steam generator, and Fig. 2 is a cross section of the same.

The direct heating surface consists, as shown, of rotating cylinders 1. In the boiler shown are three such cylinders provided. 100 Their number is fixed with regard to the highest temperature wanted in the firebox. The cylinders rotate preferably with so great velocity that the water, which is admitted into them continuously, disperses all 105 along the circumference. Thus, the central parts of the cylinders constitute the steam 110

space. After the flue gases have passed the direct heating surface, they contain still a considerable quantity of heat, which is utilized through a "fixed" heating surface, in 5 the drawing shown as a water tubular boiler 2.

The object of my invention is to provide a method and means that may be used for very high pressures, though it may also be 10 used for ordinary steam pressures. Steam generators hitherto known for generating steam of high pressure are all water tube boilers with tubes of very small diameter. Thus the direct heating surface is very 15 small so that the temperature of the firebox at only a slight strain of the grate surface becomes very high. When the water in such a tube evaporates, the volume of the steam is much greater than the water and the mixture of steam and water has a very low 20 capability of absorbing heat compared with boiling water, from which the steam bubbles can escape freely. Thus the smaller the area of the pipe, the sooner the pipe will 25 be overheated and burst. By this invention the direct surface always is covered by a layer of boiling water, and by using a suitable number of rotating vessels the temperature of the firebox may be determined beforehand 30 so that no overheating of the material can take place.

The relation between the rotating and the fixed heating surface ought to be calculated so that the water in the fixed heating surface 35 is heated to the same or a higher temperature than the temperature of saturated steam generated in the rotating heating surface. This latter steam may then be admitted into the smoke passages of the fixed heating surface and there be superheated in a special 40 superheater 4 from which it is taken out for use.

I claim:

1. The art of producing steam of high pressure for power and heating purposes which 45 consists in feeding a continuous supply of water axially to a hollow rotary tightly closed cylinder, subjecting said water to a centrifugal force which distributes it in an annular 50 layer around the peripheral interior of said cylinder by rapid rotation thereof, subject-

ing said layer to a furnace heat imparted by conduction through the wall of said cylinder, the steam generated thereby being inclosed under high pressure within said cylinder and surrounded by the centrifugally and continuously formed water layer, and withdrawing steam at high pressure from the central zone of said cylinder. 55

2. The art of producing steam of high 60 pressure for power and heating purposes which consists in subjecting feed water to a heating operation, feeding a continuous supply of so heated feed water to a hollow rotary tightly closed cylinder, subjecting said 65 water to a centrifugal force which distributes it in an annular layer around the peripheral interior of said cylinder by rapid rotation thereof, subjecting said layer to a furnace heat imparted by conduction through 70 the wall of said cylinder, the steam generated thereby being inclosed under high pressure within said cylinder and surrounded by the centrifugally and continuously formed water layer, and withdrawing steam 75 at high pressure from the central zone of said cylinder.

3. The art of producing steam of high 80 pressure for power and heating purposes which consists in feeding a continuous supply of water axially to a hollow rotary tightly closed cylinder, subjecting said water to a centrifugal force which distributes it in an annular layer around the peripheral interior of said cylinder by rapid rotation thereof, subjecting said layer to a furnace heat 85 imparted by conduction through the wall of said cylinder, the steam generated thereby being inclosed under high pressure within said cylinder and surrounded by the centrifugally and continuously formed water layer, and withdrawing steam at high pressure from the central zone of said cylinder and subjecting it to a superheating 90 operation. 95

In testimony that I claim the foregoing as my invention, I have signed my name in presence of two subscribing witnesses.

JOHAN VIKTOR BLOMQUIST.
